DOOR KNOCKER

Harold J. Marshall, Portland, Oreg.

Application June 12, 1953, Serial No. 25,476

Term of patent 14 years

(Cl. D72—1)

To all whom it may concern:

Be it known that I, Harold J. Marshall, a citizen of the United States of America, residing at Portland, county of Multnomah, State of Oregon, have invented a new, original, and ornamental Design for a Door Knocker, of which the following is a specification, reference being had to the accompanying drawing, forming a part hereof.

Fig. 1 is a front elevational view of a door knocker showing my new design;

Fig. 2 is a right side elevation; and

Fig. 3 is a top end elevation thereof.

I claim:

The ornamental design for a door knocker, as shown.
